UNITED STATES PATENT OFFICE.

DANIEL S. TROY, OF MONTGOMERY, ALABAMA.

VELOCIPED.

SPECIFICATION forming part of Letters Patent No. 317,893, dated May 12, 1885.

Application filed August 19, 1884. (No model.)

To all whom it may concern:

Be it known that I, DANIEL S. TROY, of Montgomery, in the county of Montgomery and State of Alabama, have invented a new and Improved Gas-Velocipede, of which the following is a full, clear, and exact description.

The object of my invention is to provide a new and improved velocipede which is propelled by a motor operated by the explosion of compressed gas and air, which velocipede is so constructed that it can carry a large quantity of compressed gas, can travel very rapidly, and can be steered easily.

15 The invention consists in the construction and arrangement of parts, as will be herein-after fully described and claimed.

Reference is to be had to the accompanying drawings, forming part of this specification, 20 in which similar letters of reference indicate corresponding parts in all the figures.

Figure 1 is a longitudinal elevation of my improved gas-velocipede, parts being broken out and others shown in section. Fig. 2 is a 25 plan view of the same. Fig. 3 is a longitudinal sectional elevation of the explosion-cylinder and the slide-valves, also showing the arrangement of the cranks on the driving-shaft. Fig. 4 is a plan view of the same, partly in 30 section. Fig. 5 is a cross-sectional elevation on the line $x-x$, Fig. 2. Fig. 6 is a sectional plan view on the line $y-y$, Fig. 5. Fig. 7 is a side view of the frame of the vehicle. Fig. 8 is a plan view of the same. Fig. 9 is a front 35 end view of the same. Fig. 10 is a side elevation of the cam-disks on the driving-shaft and the devices for regulating the same. Fig. 11 is an edge view of the same, parts being broken out and others shown in section. Fig. 40 12 is a side view of the cam for operating the valves for admitting the mixture of gas and air into the explosion-cylinder.

The velocipede is constructed with a suitable light and very strong metal frame in 45 which three cylindrical receptacles for the compressed gas are carried, of which receptacles, tanks, or reservoirs two (designated as A in the drawings) are arranged horizontally and longitudinally, and the third, B, is ar-

ranged transversely. The ends of the tanks 50 A are held in the front and rear frames, C and C', respectively, of the main frame A', the rear frame, C', being provided with two downwardly-projecting prongs, C², in which the crank-shaft D of the single rear driving-wheel, D', is journaled. The tanks A must be separated sufficiently to permit the wheel D' to revolve between them.

At the middle of the frame A' two circular bands, A², are formed, which surround the 55 tanks at or near the middle in the same manner as the bands or frames C C' at the ends.

On the under side of the frame A' guides B' for the cross-heads are arranged, and in front of the cross-heads circular frames or 60 rings B² are suspended from the bottom of the frame A', which rings or circular frames B² serve to hold the explosion-cylinder E and the valve-chest. On the middle bands, B², elliptical or other springs, F, are secured, which 65 support the seat F', below which a box is arranged for receiving the induction apparatus.

The several parts of the above-described frame are well braced and stiffened by suitable brace-bands.

75 On each end of the tank B, which is arranged horizontally and transversely a short distance in front of the tanks A, an outwardly-projecting pivot, G, is formed, on which the front wheels, G', are loosely mounted, and are held in place by nuts or other suitable devices, the front tank, B, thus virtually forming the forward axle of the vehicle. On the said tank B an upwardly-projecting dome, B³, is formed, from which a neck, B⁴, projects upward, which is surmounted by a steam-gage, G², which, however, can be connected with the neck B⁴ in any suitable manner.

80 On the front ends of the tanks A necks H are formed, which are united to form a hollow collar, H', around the neck B¹, projecting upward from the dome B³, the said collar being provided at the top and bottom with suitable packing-strips, so as to cause the collar to fit very closely.

90 That part of the neck B⁴ surrounded by the collar H' is provided with a series of apertures, a, which establish communication be-

tween the neck, the said collar, and the tanks A, thereby also establishing communication between the tanks A A and B.

Arms b project upward from a collar, h, on neck B⁴, above ring H', and arms c project downward from a collar, h', below collar H', on the free ends of which arms b c the rings b' and c' are secured, which surround and are secured to the neck B⁴ and the dome B³, respectively, as shown in Fig. 5, thus holding the collar H' in the proper place in relation to the neck B⁴, and preventing undue twisting-strain on the collar and neck. The neck B⁴ can turn within the collar H', and the collar H' between the collars h h'.

Rods or arms d project in opposite directions from the ring b', and are connected by connecting-rods d' with a transverse lever, e, pivoted centrally on the platform F² in front 20 of the seat F', from which cross rod or lever e a shaft, f, projects upward, and is provided at its upper end with a transverse handle, f', in front of the seat F', whereby the person occupying the seat is enabled to turn the dome B³, the neck B⁴, and the tank B very easily on the longitudinal vertical axis of the dome B³ and the neck B⁴, for steering the vehicle. A screw plug or cock, g, projects from the front of the dome, and serves to connect the tanks 25 with a pipe, through which the compressed gas is conducted to the said tanks.

The cylinder E is ring-shaped and surrounds another cylinder, E', which is closed at both ends, the cylinder E being open at one end. 30 The cylinder E contains a ring-shaped piston, J, and the cylinder E' contains a circular piston, J'. The piston-rod J², projecting from the piston J', and through a stuffing-box in the end of the cylinder E', is connected with a 35 forked connecting-rod, J³, having its ends pivoted to two cranks, K', on the driving-shaft K.

From the piston J two piston-rods, L, project, which are connected by connecting-rods 40 L' with two cranks, L², on the driving-shaft K, the cranks L² projecting in the reverse direction of the cranks K'.

At the closed end of the outer cylinder, E, a mixing-chamber, M, is formed, which is 45 connected by a channel, M', with the cylinder E', which channel can be closed by a valve, M², connected with a rod, M³, adapted to be acted upon by a lever, M⁴, pivoted on the end of the cylinder.

50 A sliding rod, N, held in the front end of the cylinder E', is adapted to act on the lever M⁴, and is pushed outward by the piston J' when the same moves toward that end of the piston in which the rod is held. A contact-piece, m, on the end of the lever M⁴, is connected with an electric lighter or spark-producing device, O, held in the end of the cylinder E', which spark-producing device is connected by a wire, o, with the induction-coil P 55 in the seat-box, the said coil being connected by a wire, o', with a contact-piece held on an

arm, q, projecting from the end of the cylinder E'.

The valve-chest P' is connected by a pipe, P², with the gas-tanks, and by a pipe, Q, with 70 the outer air, and is also provided with a pipe, Q', for the exhaust of the gases of explosion.

Two sets of valves are used, one for admitting the gas and air into the chest, and the other for admitting the gas and air into the 75 explosion-chamber. The first set is mounted on a rod, R, and the second on a rod, S. A pipe, T, connects a channel, T', in the valve-chest P' with the cylinder E'. The arrangement of the valves need not be fully described, 80 as I have described them and their operation fully in previous applications.

The valves S' and S² on the rod S always have the same reciprocating motion; but the valves R' and R² on the rod R must be so arranged that they can be adjusted. The rod R is connected with a pivoted lever, U, on the lower end of which an anti-friction roller, U', is mounted, which projects over the edges of two cam-disks, W and W', of which the former is rigidly mounted on the shaft K, and the latter is mounted on a sleeve, V, on the shaft K, the said sleeve being provided at the opposite end with a cog-wheel, r, with which two rack-bars, s, engage, the said rack-bars being 90 arranged to slide in grooves or between guides on a disk, I, mounted rigidly on the shaft K. From the rack-bars s pins t project through slots t' in the disk I, and are connected by rods I' with a grooved collar, l, mounted loosely on 100 the shaft K, in the annular groove of which collar l the forked end of a lever, k, is held, which is pivoted to the outside of one of the tanks A, and extends up to the seat F'.

The pipe P² is provided with a valve connected with a lever, P³, extending up to the seat, by means of which lever the valve can be opened or closed at will.

The rod R is jointed, and at one end is surrounded by a spiral spring, R³, which presses 110 it in the direction toward the valve-chest. The rod S is also jointed, and is pivoted to a lever, S³, provided in its lower end with a pin, S⁴, which projects into a cam-groove, Y', in a disk, Y, mounted rigidly on the shaft K. The 115 cam-disks for operating the two sets of valves are arranged on the shaft at opposite ends.

The operation is as follows: By means of the steering device described above the front tank, B, and the dome and neck formed on the 120 same can easily be turned on the vertical central axis of the dome and neck, and thus the vehicle can be steered easily and rapidly. To start the vehicle, it must be pushed after the valves have been opened to cause the contact 125 to be closed and one explosion made; or it can be so adjusted that the explosion will follow after a very slight movement of the wheels. Compressed gas passes into the cylinder E, where it expands and drives the piston J in 130 the direction of the arrows a', the piston J' moving in the inverse direction of the arrow

a' at the same time. The expanded gas is then mixed with air in the chamber M, the piston J' strikes the rod N and pushes it in the inverse direction of the arrow a' , opening the valve M², and permitting the mixture of gas and air to pass from the chamber M into the cylinder E'. Then the electric circuit is closed, a spark is produced, and the mixture of gas and air exploded, whereby the piston J' is driven in the direction of the arrow a' , and the piston J moves in the inverse direction of the arrow a' . During the movement of the piston J' in the inverse direction of the arrow a' air is drawn into the cylinder E' by means of the pipe T and the channel T' in the valve-box P'. During the stroke of the piston J' in the direction of the arrow a' the air in the cylinder E' is forced through the pipe T and the channel T', and through channels in the valve-box into the chamber M, where it is mixed with the gas, and so on, the piston J' and the cylinder E' thus serving as a pump for supplying the required quantity of air to produce an explosive mixture.

25 The valves on the rods R and S are operated from the cams W, W', and Y by means of the levers U and S³. The movements of the valves S' and S² on the rod S are always the same, independently of the quantity of gas and air admitted into the explosion-cylinder. The movements of the valves R' and R² must be changed according to the quantity of gas and air to be admitted. When the cams W and W' act on the lever U to pull the rod R from the valve-chest P', the spring R³ is compressed, and as soon as the roller U' on the lower end of the lever U runs on the raised part of the cams, the spring R³ expands and throws the lever R toward the valve-chest very rapidly. As long as the roller U' on the lower end of the lever U runs on the raised part of the cams, the valve R² keeps the gas-inlet P² closed, and as soon as the roller U' runs off of the raised parts of the cams the valve R² is moved from the gas-inlet P², thus permitting the gas to pass into the mixing-chamber M. If the cams W W' are so adjusted that the roller U' runs on the raised parts for a long time, very little gas will be admitted into the mixing-chamber, and if the cams are so adjusted that the roller U' runs on the raised parts of the cams a very short time, a comparatively greater quantity of gas will be admitted. For this reason I have provided means for adjusting the cams W W' in such a manner that the roller U will run a greater or less time on the raised parts of the said cams. By moving the sliding collar l from the disk I by means of the lever k, which extends up to the seat, the rack-bars s are moved toward each other—that is, inward or toward the middle of the disk I—and thereby revolve the sleeve V and the cam W' on the same in the direction of the arrow a^2 , Fig. 10, and thus extending the raised part of the united cams, and in this position but very little gas will be admitted into the mixing-chamber, as the roller U' runs on the lower parts of the

cams but a very short time. If the speed is to be increased, more gas must be admitted into the explosion-cylinder, and this is accomplished by moving the collar l in the direction toward the disk I, whereby the racks s will be moved from each other, and will turn the sleeve V and the cam W' on the same in the inverse direction of the arrow a^2 , thus decreasing the entire length of the raised part of the combined cams, and causing the roller U' to run a greater length of time on the lower parts of the cams, whereby the gas-inlet valve will be held open a greater length of time. The speed and power of the machine can thus be controlled very easily, and the machine can be governed in every respect by the person occupying the seat F'.

Having thus described my invention, what I claim as new, and desire to secure by Letters Patent, is—

1. In a velocipede, the combination, with a vehicle-frame, of two gas-tanks held longitudinally in the said frame, a rear driving-wheel located between the tanks, a transverse front gas-tank adapted to revolve in the horizontal plane, and wheels mounted on the ends of the transverse tank, substantially as herein shown and described.

2. In a velocipede, the combination, with a vehicle-frame, of two longitudinal gas-tanks, A, and the transverse gas-tank B, having a dome, B³, on which a neck, B⁴, is formed, and of the united necks H, secured on the front ends of the tanks A and surrounding the neck B⁴, substantially as herein shown and described.

3. In a velocipede, the combination, with a vehicle-frame, of two longitudinal tanks, A, the transverse tank B, provided with a dome, B³, and a neck, B⁴, the necks H, secured to the front ends of the tanks A and united by a collar, H', surrounding the neck on the dome, the arms b c, projecting upward and downward from the collars h h', and the rings b' and c' on the ends of the arms b and c, substantially as herein shown and described.

4. In a velocipede, the combination, with a vehicle-frame, of two longitudinal tanks, A, the transverse tank B, provided with a dome, B³, and a neck, B⁴, the necks H, secured to the front ends of the tank A, and united by a collar, H', surrounding the neck on the dome, the arms b c, projecting upward and downward from the collars h h', the rings b' and c' on the ends of the arms b and c, the arms d, projecting from the top ring, b', the connecting-rods d', the transverse rod e, the shaft f, and the transverse handle-bar f', substantially as herein shown and described.

5. A velocipede constructed with a skeleton frame provided with two rings or frames at the front and rear, and rings at the middle for holding the two tubular gas-tanks longitudinally, substantially as herein shown and described.

6. A velocipede constructed with a frame

provided with two rings at the front and rear for holding the tubular gas-tanks, and of downwardly-projecting arms at the rear in which the rear axle is journaled, substantially as 5 herein shown and described.

7. A velocipede constructed with a frame having two rings at the front and rear for holding tubular gas-tanks, and with hangers

projecting downward for holding a cylinder and valve-chest, substantially as herein shown 10 and described.
